Attorney

UNITED STATES PATENT OFFICE

JOSEPH POKORNEY, OF BALTIMORE, MARYLAND

QUICK DETACHABLE LAMP

Application filed May 1, 1931. Serial No. 534,380.

This invention appertains to new and useful improvements in electrical incandescent lamps, and more particularly to a lamp of the quick detachable type.

5 The principal object of this invention is to provide a lamp which can be quickly inserted and quickly removed from the conventional threaded types of lamp sockets.

10 During the course of the following specification and claim, other important objects and advantages of the invention will become apparent to the reader.

In the drawing:—

15 Figure 1 represents a fragmentary side elevational view of the lamp.

Fig. 2 represents a fragmentary side elevational view of the lamp showing the detents in a different position.

20 Fig. 3 represents a fragmentary detailed sectional view of the lamp engaged in a socket.

Fig. 4 represents a fragmentary detailed sectional view showing a modification of the invention engaged into a conventional socket.

25 Fig. 5 represents a fragmentary detailed sectional view taken substantially on the line 5—5 of Fig. 4.

Referring to the drawing wherein like numerals designate like parts, it can be seen that numeral 5 represents the shell of a conventional lamp socket which has been stamped to provide the threads 6. At the inner end of the socket 5 is the usual spring 7, with which the central contact 8 on the

30 lamp base 9 engages.

To facilitate quick attachment and detachment of the lamp with respect to this conventional type of socket, a detent such as is generally referred to by numeral 10 is provided on the base 5 along with transversely ribbed plates 11.

35 This detent 10 is substituted for one of the plates 11 and consists of a leaf spring 12 secured at one end as at 13 to the outer end portion of the base 9. The spring 12 is offset outwardly as at 14 adjacent the portion 13 and then extends along the side of the base 9 and for a short distance of the neck portion of the globe 15.

40 50 This latter portion of the spring 12 is pro-

vided with a di-electric covering 16. A spring 17 is secured at one end to the base 9 opposed to the intermediate portion of the spring 12 and bears against the latter to normally maintain the latter in an offset urged 55 position.

The outer side of this spring 12 is provided with the outwardly extending teeth 18 which engage with the threads 6 of the socket 5 to maintain the base 9 of the lamp in the socket. 60 The spring action of the springs 12 and 17 also serves to maintain the ribs on the plates 11 engaged with the threads 6.

Fig. 4 shows a modification of the invention wherein the base 9 is provided with a 65 bracket 19, the major portion of which is spaced from the base 9 while its end portions are secured to the base. One end portion of the bracket 19 is bifurcated to provide a space 20 through which the leaf spring 21 protrudes. The end of the spring 21 within the bracket 19 is secured to the outer end of the bracket and this spring 21 is provided with a tooth 22 operative through an opening 23 in the bracket 19 to engage the teeth 23 70 of the lamp socket 5.

75 The outer free end of the spring 21 is provided with a di-electric covering 24. Thus it can be seen, that by moving the di-electric plug of the spring 21 toward the bulb 15, the tooth 22 is disengaged from the threads 23 so that the lamp can be inserted into the 80 socket or removed therefrom.

85 Obviously, when the base 9 is inserted into the socket and the spring 21 released, the tooth 22 will engage in the threads 23 to prevent displacement accidentally of the lamp from the socket. This same action takes place in manipulating the form of the invention shown in Fig. 3.

90 While the foregoing specification sets forth the invention in specific terms it is to be understood that numerous changes in the shape, size and materials may be resorted to without departing from the spirit and scope of the 95 invention as claimed hereinafter.

Having thus described my invention, what I claim as new is:—

In an electric lamp, a base for the lamp, a leaf spring member secured at one end to 100

the base and being diverged outwardly from the base at its remaining end, a tooth on the member, a bracket for the spring having an opening therethrough, through which the
5 tooth is operative, said bracket serving as a stop to limit outward movement of the member.

In testimony whereof I affix my signature.

JOSEPH POKORNEY.
